UNITED STATES PATENT OFFICE

JOHN F. MELVIN, JR., OF NEW YORK, N. Y.

SOUND RECORDING APPARATUS

Application filed December 14, 1929. Serial No. 414,010.

Among the principal objects which the present invention has in view are: to record sound waves photographically for reproduction in coordination with kinetic photographs of persons or things; and to produce said records noiselessly.

Drawings

Figure 1 is a schematic view showing parts of the apparatus arranged as in service.

Figure 2 is an end view of the vibrating mechanism employed in the present apparatus.

Figure 3 is a longitudinal section of the same, the section being taken as on the line 3—3 in Figure 2.

Figure 4 is a face view of a housing for the photographic film on which the photographic record is made and the vibrating diaphragm through which light is conveyed to the film, the view being taken as from the plane indicated by the line 4—4 in Fig. 1.

Fig. 5 is a detail view in cross section, and on enlarged scale, of the vibrating diaphragm and the mounting therefor.

Description

In accordance with the present invention, a photographic ribbon film 9 is employed. The film may be independent of what is known as the master or picture film upon which photographic negatives of the sound producing object or person are being photographed. If the film is independent of the said master film, then synchronizing means of any approved type is used for operating the two films simultaneously.

The said master film is not herein described or claimed. The film 9 is covered by the panel 10 and is otherwise protected from the light except where the same enters through the elongated and narrow passage or slit 11, past which the said film is being rapidly moved. The slit 11 is formed in the panel 10 in a position transverse the length of the film 9 and transverse the direction in which said film is moved.

Light is conveyed to the film through the said slit 11 and a slit 12 formed in the vibrating diaphragm 13. The slit 12 is disposed in

perpendicular relation to the slit 11 as can be seen best in Figure 4 of the drawings. The diaphragm 13 is preferably vibrated toward and away from the panel 10, and the slit 11. It is obvious that as the diaphragm 13 moves toward the panel 10, the lighter area delivered to and through the slit 11 and is diminished in width. And it is equally obvious that as the diaphragm 13 is retracted or moved away from the panel 10, the lighted area delivered through the slit 11 is widened, or increased lengthwise of the slit 11. Between the limits of the two extremes of the movement is the whole gamut of modulation in the sound produced.

In the drawings, the source of light is indicated as an electric lamp 14. This light is conveyed preferably through the open ended tubular core 15 with which the magnet 16 is provided. The core 15 is suitably wound as indicated, by the wire 17. The wire 17 is suitably connected with an electric source, the current taken therefrom serving to saturate the core to preserve and provide the contention necessary to float the small finely wound coil 18 in the magnetic field between the pole pieces 19 and 20 of the larger magnet.

The diaphragm 13 is normally suspended in concentric arrangement with the core 15 by means of pins 21 and the supporting spring brackets 22. The brackets 22 are tempered to provide sensitive springs adapted to support the diaphragm 13 in its neutral position or normal position. The windings of the coil 18 are connected by means of lead wires 23 with a suitable source of electric energy, preferably what is known as the alternating current, of desired voltage. This current is subject to modulating influences. These influences are acoustically produced through any suitable medium.

As the tension in the small coil 18 is increased and diminished, the magnetic action between it and the magnet 16 is varied.

If now the current tension in the wires 23 be varied or modulated by a suitable mechanism that can be influenced by sound waves, the tension in the coil 18 will be correspondingly influenced and the diaphragm 13 will be moved to and from the panel 10, with the

result that the light area delivered through the slit 11 is varied in direct proportion as the diaphragm is approached or receded to and from the panel 10.

When, now, the film 9 is developed, a light path is produced, the width of which is momentarily varied. When this film is now passed between a light source and a photo-sensitive electrocell of approved type, said cell having incorporated therewith, means for varying the sending current of a radio transmitting unit embodying a sound producing mechanism, a reproduction of the sound which was instrumental in forming the said path, is repeated in the speaker.

When desired, lenses such as indicated by the numeral 24 may be employed effectively for concentrating or intensifying as the case may be, the light transmitted from the element 14.

While there has been herein described means for varying the width of the light path, said means employing a passage of a given height and a vibrating obscuring diaphragm having a corresponding or cooperating slit or narrow passage, the movement of which, to and from the first named passage, varies the width of the light path, I may produce the same result or the close equivalent thereof by employing a mirror or reflector arranged to direct the pencil of light through said passage, said ray operating from the edge of the film as a base or neutral line in the manner and as now produced. But in accordance with the present invention, the reflector will be moved in correspondence with the movement of the coil 18.

I claim:

1. A sound recording apparatus comprising means for moving a photo-sensitive film at a fixed rate of speed, a covering member stationarily disposed in juxtaposed relation to said film, said covering member having an elongated narrow slit extending transverse the path of movement of said film, a stationary illuminating element for delivering light through said slit, a movable obscuring member reciprocatively disposed between said covering member and said illuminating element, said obscuring member having an elongated light passage therein aligned with said slit for varying the width of the light ray, reaching said film through said slit, and electro-active means for reciprocating said obscuring member to and from said covering member in correspondence with the electro impulses received by said electro-active means.

2. A sound recording apparatus comprising means for moving a photo-sensitive film at a fixed rate of speed, a covering member stationarily disposed in juxtaposed relation to said film, said covering member having an elongated narrow slit extending transverse the path of movement of said film, a

stationary illuminating element for delivering light through said slit, a movable obscuring member reciprocatively disposed between said covering member and said illuminating element, said obscuring member having an elongated light passage therein aligned with said slit for varying the width of the light ray reaching said film through said slit, and electro-active means for operating said obscuring member in correspondence with electro impulses received thereby, said means embodying an electro-magnet having a tubular core disposed in line with and between said illuminating element and said passage in said obscuring member.

3. A sound recording apparatus comprising means for moving a photo-sensitive film at a fixed rate of speed, a covering member stationarily disposed in juxtaposed relation to said film, said covering member having an elongated narrow slit extending transverse the path of movement of said film, a stationary illuminating element for delivering light through said slit, a movable obscuring member reciprocatively disposed between said covering member and said illuminating element, said obscuring member having an elongated light passage therein aligned with said slit for varying the width of the light ray reaching said film through said slit, and electro-active means for operating said obscuring member in correspondence with the electro impulses received thereby, said means embodying an electro-magnet having a tubular open core interposed between said illuminating member and said obscuring element, and electro-active means supporting said obscuring member to float between the fields of said electro-magnet, said magnet being adapted to receive a continuous electric current arranged to be modulated by a suitable sound transmission apparatus.
